(57) CLAIM

I claim the ornamental design for a weapon sighting device, as shown and described.

DESCRIPTION

FIG. 1 is a front, top, right side isometric view of a weapon sighting device;

FIG. 2 is a left side view of the weapon sighting device of FIG. 1;

FIG. 3 is a top view of the weapon sighting device of FIG. 1;

FIG. 4 is a right side view of the weapon sighting device of FIG. 1;

FIG. 5 is a bottom view of the weapon sighting device of FIG. 1; and,

FIG. 6 is a rear view of the weapon sighting device of FIG. 1; and,
FIG. 7 is a front view of the weapon sighting device of FIG. 1.

1 Claim, 3 Drawing Sheets

Matter enclosed in heavy brackets [ ] appears in the original patent but forms no part of this reissue; matter printed in italics indicates the additions made by reissue.
